UNITED STATES PATENT OFFICE.

DAVID G. McCAA, OF LANCASTER, PENNSYLVANIA, ASSIGNOR TO THE ELECTRIC APPARATUS CO., OF PARKESBURG, PENNSYLVANIA, A CORPORATION OF PENNSYLVANIA.

RECEIVING SYSTEM.

Application filed November 17, 1922. Serial No. 601,455.

To all whom it may concern:

Be it known that I, DAVID G. McCAA, a citizen of the United States, residing in Lancaster, county of Lancaster, State of Pennsylvania, have invented new and useful Improvements in Receiving Systems, of which the following is a specification.

My invention relates to a method of and apparatus for eliminating or reducing the effects of electrical disturbances in the reception of signals, telegraphic, telephonic or otherwise, represented by alternating current, and particularly alternating current or oscillations of radio frequency.

15 In accordance with my invention, the effects of static, atmospherics, strays and other natural or artificial disturbances including other radio signals, are reduced or eliminated in a radio or other receiving system, whereby 20 the desired signals are readily distinguishable or become intelligible notwithstanding the simultaneous existence of strong disturbing effects.

In accordance with my invention, the received energies representing both the desired signal and the disturbing effect are divided into paths including reactive devices, one of which is employed for effecting the translation of the desired signals, and with another 30 of which is associated a local source of alternating current or oscillations in such wise as to cause the effect of said other reactance to fluctuate within wide limits and thereby causing the signal-representing 35 energy in the first reactance to fluctuate in amplitude and at certain instants to be reinforced by energy from the local source, to the substantial exclusion or great reduction of the effects of the simultaneously existing 40 disturbing energy.

In accordance with my invention, the aforesaid current locally produced has a frequency which preferably is different from the frequency of the energy representing the 45 desired signal, though it may be of the same frequency as hereinafter described, and in either or both cases it is preferred that the locally produced energy in its reaction with the oscillations representing the desired signal and the disturbing effects shall be substantially equal to the amplitude of the oscillations of the desired signal, whereby the ratio of the effect upon the signal translating instrument of the energy representing

the desired signal to the effect upon that instrument of the energy representing the simultaneously existing disturbing energy is increased, as compared to what would be the normal effects of the signal-representing energy and the disturbing energy were my invention not employed.

My invention resides in the method and apparatus hereinafter described and claimed.

For an understanding of my method and for an illustration of some of the many forms my apparatus may take, reference is to be had to the accompanying drawing, in which:

Fig. 1 is a diagrammatic view of circuit arrangements embodying my invention. 70

Fig. 2 is a fragmentary diagrammatic view illustrating a modification.

Fig. 3 is a diagrammatic view of a modification where the corrective circuit or device is applied in a secondary circuit. 75

Fig. 4 is a diagrammatic view of a modified system wherein my corrective device is in effect in series with the receiver coil.

Fig. 5 is a diagrammatic view of a system involving my corrective device in a modified arrangement. 80

Referring to Fig. 1, A represents the antenna or other absorption structure of a radio or any other receiving system, connected through the variable inductance L and the primary P of an oscillation transformer to earth or other counter-capacity E, the variable condenser C serving to tune the antenna path and the circuit including the primary P to the frequency of the oscillations produced in the antenna system by the energy absorbed from the natural or other medium. Inductively related to the primary P is the secondary S of an oscillation transformer whose circuit, particularly for long wave reception, may include the adjustable inductance L¹. For tuning the secondary circuit, there is provided the usual tuning condenser C¹, whose terminals are connected to the grid circuit of the audion or other vacuum tube detector-amplifier V comprising the filament or cathode f, grid g, and anode or plate a. 90

In the grid path may be connected the condenser C², shunted by the leak resistance r. In the anode circuit of the tube V is the source of current or battery B and a winding T, which may be the winding of a telephone receiver, or may be the primary of a trans-

former delivering the plate circuit current or a component thereof to one or more stages of radio or audio frequency amplifying devices, as well understood in the art, the condenser C^2 and the resistance r being omitted when the amplification is to occur at radio frequency. In shunt to the winding T may be connected the condenser C^3 when the winding T is that of a telephone or the primary of an audio frequency transformer, the condenser C^3 being omitted in the case where the winding T is the primary of a radio frequency transformer, all as well understood in the art.

15 As thus far described, the receiving apparatus is a usual one and per se is not my invention.

However, in accordance with my invention, there is connected in parallel with the primary P , or in any other divided or suitably related path or position therewith as regards the antenna circuit or other path traversed by the oscillations of the desired signal and the simultaneously existing disturbing effect, a reactance, either capacitative or inductive, but preferably, as shown, an inductive reactance L^2 , whose amount may be adjustable as indicated. It is preferred that the resistance of the inductance L^2 shall be small as compared with its inductance. The magnitude of the inductance L^2 is preferably so chosen that its reactive effect is great compared with that of the primary P for oscillations of the frequency corresponding with that of the desired signal, whereby, if the reactances L^2 and P only were present, the oscillations representing the desired signal attain a far greater magnitude in the primary P than in the inductance L^2 .

40 However, the reactance or inductance L^2 by itself is insufficient for my purposes, and there is connected in series therewith a variable condenser C^4 , which may be connected as indicated, and preferably, to the terminals of additional inductance in series with the inductance L^2 , this additional series inductance being indicated at L^3 , and may be in effect a continuation of the inductance L^2 and forming therewith in effect an autotransformer. For a given frequency of the oscillations representing the desired signal, the capacity of the condenser C^4 may be adjusted to a value with respect to the magnitude of L^3 , L^3 which causes the reactance of the path L^3 , C^4 , L^3 in shunt to inductance L^2 for that frequency to vanish or become zero or substantially zero, whereby, under such condition and for such time, the effect is the same as if the reactance of inductance L^3 were reduced to zero because primary P is substantially completely robbed of signal-representing energy. That is to say, this effect is the same as if inductance L^2 were short circuited or as if the leads to the two terminals of the inductance L^2 were brought into low resistance conductive contact with each other. The magnitude of the capacity of the condenser C^4 for this condition is not that which would be given to the condenser C^4 to tune the control circuit L^2 , L^3 , C^4 by itself or when isolated, to the frequency of the oscillations representing the desired signal, but has been found to be considerably greater, and for long wave lengths, as of the order of 13,000 meters, is substantially three or four times as great. In operation of the system, this large desired value of the capacity of the condenser C^4 is found by trial by manually adjusting the condenser to produce optimum effect.

70 If the control circuit L^2 , L^3 , C^4 with such large value of capacity of the condenser C^4 is opened, the reactance or impedance across the terminals of the inductance L^2 resumes its initial or normal value, with the result that in the primary P the amplitude of signal-representing oscillations would again be large. Therefore, by periodically interrupting the circuit L^2 , L^3 , C^4 the amplitude of signal-representing oscillations in the primary P will be alternately large and substantially zero.

75 What has been said of the oscillations representing the desired signal is also true of those oscillations simultaneously present in the antenna system and due to the absorption thereby of the energy representing the disturbing effects of static, atmospherics, strays, etc., which energy, due to the fact that the antenna system is attuned to the frequency of the desired signal, causes in the antenna system and the windings P and L^2 oscillations of the same frequency as the oscillations representing the desired signal.

80 Therefore, when the circuit L^2 , L^3 , C^4 is open, the amplitude of the oscillations in the primary P , representing both the desired signal and the disturbing effect, is large, and when the aforesaid control circuit L^2 , L^3 , C^4 is closed, the amplitudes of the two sets of oscillations in the primary P are substantially nil.

85 With the apparatus thus far described, the effects of static, etc., have not been reduced or eliminated, as distinguished from the signal-representing energy; both are absent from the receiving apparatus represented by the primary P when the control circuit L^2 , L^3 , C^4 is closed, though both are present in said control circuit and the remainder of the antenna path, and both are present in the receiving apparatus when said circuit L^2 , L^3 , C^4 is open.

90 However, to greatly reduce the effects of static or other disturbances, there is placed in inductive relation to the control circuit L^2 , L^3 , C^4 , or to any suitable part thereof, as one of the inductances L^3 , a coil D , prefer-

ably movable or rotatable with respect to the coil L^3 , for varying the coupling between them. There is caused to pass through the coil D , from a local source or generator of 5 high frequency oscillations, oscillations of a frequency equal to or different from the frequency of the oscillations representing the desired signal and the disturbing static or other effect. Preferably, however, the frequency of the oscillations traversing the coil D is different from the frequency of the oscillations representing the desired signal and the disturbing effects of static, etc., and so much different therefrom that the beat is 10 of audible frequency for telegraphy and is of super-audible or inaudible frequency for telephony.

When the frequency of the oscillations traversing the source D is equal to the frequency of the oscillations representing the desired signal and the interfering static effects, the apparatus is utilizable for telephony.

By way of example, merely, the local 25 source of oscillations is an oscillating audion V^1 , it being understood, however, that any other suitable source may be employed.

Assuming the oscillations representing the desired signal to be weak or to have small 30 amplitude, and the interfering effects, as static, strays, etc., to be of great amplitude or relatively strong, the oscillations representing the desired signal have an amplitude which is small compared with the amplitude 35 of the oscillations set up in the receiving antenna or other circuit by the atmospherics, strays, static, etc.

In order that the strong oscillations representing the disturbances shall not maintain 40 their relative strength in their effect upon the telephone or other instrument T , the coil D is rotated or moved to such position with respect to the coil L^3 that the amplitude of the oscillations induced in L^3 by 45 the coil D shall be substantially equal to the amplitude of the oscillations representing the desired signal, though simultaneously there exist in the circuit L^2 , L^3 , C^4 oscillations representing the static or other disturbances of an amplitude which is relatively 50 great with respect to the amplitude of the oscillations of the desired signal.

There accordingly occurs in the circuit L^2 , L^3 , C^4 reaction by the weak oscillations induced in that circuit by the coil D upon the oscillations representing the desired signal, and also upon the oscillations of relatively far greater amplitude representing the disturbing effects of static, etc. There are accordingly 55 produced two sets of beats. The first set is the beats produced by reaction with the oscillations of small amplitude representing the desired signal, and these beats are full or perfect in the sense that the signal waves are non-decadent, and, secondly, 60 in that the beat amplitude varies between substantially zero and twice the amplitude of the oscillations representing the desired signal. The other set of beats is that produced with the oscillations of relatively far 65 greater amplitude and representing static, etc., and these beats are imperfect, first in the sense that the oscillations representing static are generally decadent, and secondly, because the amplitude of the oscillations 70 representing static is great compared with the amplitude of the reacting oscillations induced by the coil D , with the result that the beats whose components are the weak oscillations from D and the strong oscillations 75 representing static, etc., a maximum amplitude which is only relatively slightly greater than the amplitude of the oscillations representing static, etc., while in the case of the 80 beats effected by means of the oscillations of lesser amplitude representing the desired signal the maximum beat amplitude is about twice the amplitude of the signal oscillations; that is to say, the effect of the oscillations from the local source D upon the amplitude of the beats caused by oscillations 85 representing static, etc. is proportionately smaller than the effect upon the amplitude of the beats due to the oscillations representing the desired signal.

Accordingly, during the presence of oscillations of small amplitude representing the desired signal in the circuit L^2 , L^3 , C^4 , there is a time when the resultant of the reaction thereof with the oscillations of equal amplitude induced by the coil D is substantially zero, and the reactance across the terminals of the inductance L^2 is the normal one corresponding to the conditions of opening the circuit L^2 , L^3 , C^4 ; at another period the oscillations representing the signal and induced by the coil D are cumulative, and there is flowing in the circuit L^2 , L^3 , C^4 a signal-representing current of substantially 100 double amplitude; and under these circumstances, the condenser C^4 having the aforesaid capacity, the reactance between the terminals of the inductance L^2 is substantially zero. The result is, therefore, that in the primary P , and therefore in the signal-translating instrument T , the effect of the oscillations representing the desired signal 105 is alternately zero and a maximum, as if the inductance L^2 and its associated parts were absent and the primary P only subjected to the oscillations representing the desired signal. When the oscillations induced by the coil D are in opposition to the oscillations representing the weak signal, there is 110 a cumulative effect in the primary P of the locally produced oscillations and those representing the desired signal; and vice versa, when the local and signal oscillations are cumulative or assist each other in the circuit 115 of the condenser C^4 , they oppose each other 120

in the primary P. That is to say, in addition to the aforesaid fluctuations in magnitude of effects upon the receiving instrument, as the signal-translating instrument 5 T, the oscillations traversing the coil D produce an effect upon the primary P, and therefore upon the signal-translating instrument T, cumulative with the aforesaid signal effects because coil D can affect the primary P when the impedance of L² is at its normal value, as if the circuit L², L³, C⁴ were open.

It will therefore be apparent that the circuit L², L³, C⁴ is one which has, particularly 15 in the relation here utilized, a peculiar characteristic, in that when a fluctuating or alternating current of certain magnitude is flowing therein, the impedance across the terminals of L² is small or zero, or when 20 there is zero or substantially zero current in the circuit L², L³, C⁴, the impedance or reactance across the terminals of the inductance L² is its normal one, as if said circuit were open. In other words, the arrangement 25 and mode of operation are such that the inductance L² may be said to exhibit normal or substantially zero reactance, according as the current in the circuit including the condenser C⁴ is zero or of finite value.

Assuming now that there exists simultaneously with the oscillations representing the desired signal oscillations of far greater amplitude representing static or the like, there is in the circuit of the condenser C⁴, 35 due to the oscillations representing static or the like, a beat current which does not fall to zero, but fluctuates between narrow limits at relatively high amplitude. Accordingly, as regards the beat current due to static or 40 other effect, the impedance or reactance across the terminals of the inductance L² is small or zero, and no more static effect reaches the primary P and signal-translating instrument T than corresponds with 45 the amplitude of the oscillation induced in the circuit of the condenser C⁴ by the coil D.

Accordingly, by choosing the amplitude of the oscillation induced in the circuit of the condenser C⁴ by the coil D of a magnitude substantially equal to that of the oscillations representing the desired signal, the impedance or reactance across the terminals of the inductance L² is low or zero for all of 50 that part of the energy representing static except that part which is comparable to the amplitude of the oscillation induced by the coil D, with the result that the effect upon the primary P, and therefore upon the signal-translating instrument T, of static 55 is no greater than that of the desired signal effects.

In other words, by the employment of the condenser C⁴ of the desired magnitude and its circuit, the greater portion of the relatively greater effect due to static is withheld

from the primary P and signal-translating instrument T because of the then correspondingly low or zero reactance across the terminals of the inductance L².

Viewing the matter in another way, there exist simultaneously in the circuit of the condenser C⁴ oscillations of great magnitude representing static and oscillations of relatively small magnitude representing the desired signal; these oscillations produce reaction with the weak oscillations induced by the coil D resulting in beat effects in the circuit of the condenser C⁴, which, as regards variation of amplitude of the beat effects, are substantially equal for both the static and signal effects, and the remaining large portion of the effect due to static, represented by current flowing in the circuit of the condenser C⁴, reduces the impedance or reactance across the terminals of the inductance L² to substantially zero value, with the result that when strong static is present with weak signals, the circuit of the condenser C⁴ is substantially open at such times as the oscillations induced by D and the weak signal oscillations are in opposite phase and neutralizing each other, and a signal is therefore manifested at T, because the reactance across the terminals of the inductance L² is great under such condition; while as regards the strong static effects, the weak oscillations induced by the coil D do not completely annul the static oscillations in beat formation, and therefore, as regards the static effects, there is always substantial current flowing in the circuit of the condenser C⁴, and for such static effects, therefore, the reactance across the terminals of the inductance L² is small or zero, and such strong static effects are therefore withheld from the primary P and the signal-translating instrument T.

When the frequency of the oscillations induced by the coil D is equal to the frequency of the oscillations representing the weak signal and also the strong static, beat effects are produced, or beats of zero frequency are produced, the characteristic action being the same in that the predominant effects of static cause the reactance across the terminals of the inductance L² to be zero or small, and therefore produce no effect upon the signal-translating instrument T, and only that portion of the energy representing static produces an effect upon the instrument T which corresponds in amplitude with the amplitude of the oscillations representing the desired signal.

In connection with the receiving circuit proper, as the circuit of the secondary S and its adjuncts, it will be found that when the condenser C¹ is adjusted to that magnitude which will attune the circuit S, L¹, C¹ to the frequency of the oscillations representing the desired signal, and with the circuit L²,

L^3, C^4 absent, the same setting of the condenser is the optimum for reception of the signals through static as above described, with the circuit L^2, L^3, C^4 present with the local source of oscillations in operation. But the condenser C^1 must be adjusted to a value of capacity greater or less than its aforesaid value to tune to the radio component of the partial beats due to static, according as the coil D is inducing in the circuit of the condenser C^4 oscillations of frequency less than or greater than the frequency of the oscillations representing the desired signal. And the greater the difference between the frequencies of the locally produced oscillations and those representing the signal, the greater is the difference in the settings of the condenser C^1 as between tuning to the frequency of the signal-representing oscillations and the radio component of the static effects. In other words, by varying the adjustment of the condenser C^1 as aforesaid, the receiving circuit may be attuned with respect to the signal-representing oscillations, and for the same setting the circuit will be de-tuned with respect to the radio component of the static effects in the same circuit.

While in the arrangement of Fig. 1 the condenser C^4 is in a circuit or path conductively related to the antenna circuit or path or directly coupled to L^2 , it may be placed in a path coupled to or inductively related to the antenna path, as indicated in Fig. 2, wherein the aforesaid inductance L^2 serves as the primary of an oscillation transformer whose secondary is an inductance L^3 , in circuit with which is the aforesaid condenser C^4 , and in inductive relation to the circuit L^3, C^4 is disposed the aforesaid coil D traversed by the locally produced oscillations. In this case the magnitudes of inductance L^3 and capacity C^4 are such as to tune to the frequency of the oscillations representing the desired signal when coupled to L^2 ; but, as before, in the case of Fig. 1, when the circuit L^3, C^4 is isolated, a smaller value of capacity C^4 will serve to tune to the frequency of the oscillations representing the desired signal.

As indicated in Fig. 3, the primary P and the inductance L^2 , correlated in the manner indicated in Fig. 1 or 2, are disposed not directly in the antenna path, but in a secondary circuit comprising the secondary S^1 , inductively related to the primary P^1 in the antenna path, the circuit of the secondary S^1 being tuned by the variable condenser C^5 , and, if suitable or desirable, by the inductance L^4 .

Referring to Fig. 4, there is shown an arrangement wherein, in effect, the corrective or control circuit is serially related to the receiver coil or primary P . In this instance the inductance L^2 of the control cir-

cuit or corrective device is in series with the receiver primary P , whether directly in the antenna circuit, as indicated, or in a secondary circuit, as indicated in Fig. 3. The inductance L^3 is closely coupled to the inductance L^2 , and, as before, the coil D is rotatable with respect to the inductance L^3 and is traversed by locally produced oscillations of a frequency equal to or different from the frequency of the received energy. In this case and that of Fig. 2, however, the magnitude of the capacity C^4 is that or more nearly that suitable for tuning the circuit L^3, C^4 to the frequency of the received energy. The secondary S of the receiving apparatus is preferably loosely coupled to the primary P .

In action, the close coupling between the coils L^2 and L^3 causes large transfer of energy to the circuit L^3, C^4 during those times that it is effectively closed by the effect of the locally produced oscillations traversing the coil D . On the other hand, the loose coupling between P and S permits suitable amount of signal energy to be transferred from P to the secondary circuit S at those times when the circuit L^3, C^4 is in effect open. When the circuit L^3, C^4 is in effect open, that is, when the impedance L^3 has its normal or maximum effect, L^2 and P , together with the condenser C , attune the antenna circuit or other path to the frequency of the received energy. While herein the condenser C is shown as in series with the antenna path, which is suitable particularly for short waves, it will be understood that it may be connected in parallel to the inductance L^2 and primary P for long wave reception.

Referring to Fig. 5, the secondary receiving circuit is, as before, associated with the primary P , with which is associated in turn a circuit L^2, L^3, C^4 , as in Fig. 1. In circuit with the primary P is a further primary P^4 of an oscillation transformer whose secondary S^4 is in the grid circuit of a thermionic or audion amplifier V^2 , in whose anode or plate circuit is the coil D in inductive relation with the circuit containing the condenser C^4 , which is adjusted to the capacity magnitude discussed in connection with Fig. 1.

The primary P^4 when traversed by feeble signal-representing oscillations, inductively affects the grid circuit of the amplifier V^2 , which in turn causes an amplified signal-representing oscillation traversing the coil D which inductively affects the circuit containing the condenser C^4 , with the result that when signal-representing oscillations traverse the primaries P, P^4 , the reactance of the inductance L^2 attains its normal or high value, forcing more signal-representing current through the primaries P, P^4 , and the action is again built up through the coil D .

in its effect upon the circuit of the condenser C^4 , until finally the signal effects in P are increased to a maximum, due to the fact that the reactance of the inductance L^3 has attained a maximum. In this case, the coil D is traversed by oscillations of signal frequency, and not of a frequency differing from that of the signal frequency or a frequency representing the static or other disturbance, and the circuit arrangement is utilizable for telephony. In shunt to the secondary S^4 may be connected the tuning condenser C^5 for tuning the grid circuit for enhancing the effects described.

15 By the arrangement of Fig. 5, signal-representing oscillations passing through the primary P are utilized in amplified form for influencing the circuit containing the condenser C^4 to effect such current strength 20 therein as to in effect open that circuit, as by the increase of reactance of the inductance L^3 , accordingly forcing more of the received signal energy through the primary P . Here again the reaction of the signal 25 frequency oscillations with the strong oscillations representing the relatively stronger static or other disturbing effect produces the result hereinbefore described in connection with Fig. 1, in that there is 30 an increase in the ratio of the magnitude of the effect in the telephone or other translating instrument T of the oscillations representing the desired signal to the magnitude 35 of the effect produced upon the instrument T by the static or other disturbing effect.

While in the foregoing description currents of radio frequency have been assumed and considered, it will be understood that my invention is not limited thereto, but in 40 its broader aspect comprises a method of and apparatus for differentiating between currents, whether of audio or radio frequency, which may be of the same frequency but of different amplitudes; or comprises a 45 method of and apparatus for reducing the difference between effects of such audio or radio frequency currents, whereby the weaker may produce a desired effect of greater relative magnitude than otherwise 50 possible.

What I claim is:

1. The method of distinguishing between fluctuating currents of different amplitudes, which comprises impressing the currents 55 upon a current-translating circuit and upon a control path upon the magnitude of whose reactance depends the magnitude of effect in said translating circuit, and rendering said reactance of small magnitude for withholding from said translating circuit effects of said current of greater amplitude.

2. The method of distinguishing between fluctuating currents of the same frequency but different amplitudes, which comprises 60 impressing the currents upon a current-

translating circuit and upon a control path upon the magnitude of whose reactance depends the magnitude of effect in said translating circuit, and rendering said reactance periodically of small magnitude for withholding from said translating circuit effects of said current of greater amplitude. 70

3. The method of distinguishing between fluctuating currents of different amplitudes, which comprises impressing the currents 75 upon a current-translating circuit and upon a control circuit including inductive and capacitative reactances, and impressing upon said control circuit a fluctuating current for rendering its reactance periodically of reduced magnitude for withholding from said translating circuit effects of the current of greater magnitude. 80

4. The method of distinguishing between fluctuating currents of the same frequency 85 but different amplitudes, which comprises impressing the currents upon a current-translating circuit and upon a control circuit including inductive and capacitative reactances, and impressing upon said control 90 circuit a fluctuating current for rendering its reactance periodically of reduced magnitude for withholding from said translating circuit effects of the current of greater magnitude. 95

5. The method of distinguishing between fluctuating current of the same frequency but different amplitudes, which comprises impressing the currents upon a current-translating circuit and upon a control circuit including inductive and capacitative reactances, and impressing upon said control 100 circuit a fluctuating current of different frequency for rendering its reactance periodically of reduced magnitude for withholding from said translating circuit effects of the current of greater magnitude. 105

6. The method of distinguishing between radio frequency oscillations representing a desired signal and oscillations of the same 110 frequency but of greater amplitude representing a disturbing effect, which comprises impressing both sets of oscillations upon a signal-translating circuit and a control circuit including inductive and capacitative 115 reactances and adapted upon reduction of magnitude of its reactance to withhold energy from said signal-translating circuit, and impressing upon said control circuit a periodic current of different frequency. 120

7. The method of distinguishing between radio frequency oscillations representing a desired signal and oscillations of the same frequency but of greater amplitude representing a disturbing effect, which comprises 125 impressing both sets of oscillations upon a signal-translating circuit and a control circuit including inductive and capacitative reactances and adapted upon reduction of magnitude of its reactance to withhold en- 130

ergy from said signal-translating circuit, and impressing upon said control circuit a periodic current.

8. Apparatus for distinguishing between fluctuating currents of different amplitudes, comprising a winding and associated current-translating means, a reactance related to said winding for withholding energy therefrom upon reduction of said reactance, a reactance of different type associated with said reactance for effecting reduction of said first named reactance to small value when said reactances are traversed by substantial current, means for impressing the currents of different magnitudes upon said winding and upon said first named reactance, and means for impressing upon said reactances a periodic current.

9. Apparatus for distinguishing between fluctuating currents of the same frequency but different amplitudes, comprising a winding and associated current-translating means, an inductive reactance related to said winding for withholding energy therefrom upon reduction of said reactance, a capacitative reactance associated with said inductive reactance for effecting reduction of said inductive reactance to small value when said reactances are traversed by substantial current, means for impressing the currents of different magnitudes upon said winding and said inductive reactance, and means for impressing upon said reactances a periodic current.

10. Apparatus for distinguishing between fluctuating currents of the same frequency but different amplitudes, comprising a winding and associated current-translating means, an inductive reactance related to said winding for withholding energy therefrom upon reduction of said reactance, a capacitative reactance associated with said inductive reactance for effecting reduction of said inductive reactance to small value when said reactances are traversed by substantial current, means for impressing the currents of different magnitudes upon said winding and said inductive reactance, and means for impressing upon said reactances a periodic current of different frequency.

11. Radio receiving apparatus for distinguishing between oscillations of radio frequency representing a desired signal and oscillations of the same frequency but greater amplitude representing a disturbing effect, comprising a winding, signal-translating means associated therewith, an inductive reactance related to said winding for withholding energy therefrom upon reduction of said reactance, a capacitative reactance associated with said inductive reactance for effecting reduction of said inductive reactance to small value when said reactances are traversed by substantial current, means for impressing the oscillations

of different amplitudes upon said winding and said inductive reactance, and means for impressing upon said reactances a periodic current.

12. Radio receiving apparatus for distinguishing between oscillations of radio frequency representing a desired signal and oscillations of the same frequency but greater amplitude representing a disturbing effect, comprising a winding, signal-translating means associated therewith, an inductive reactance related to said winding for withholding energy therefrom upon reduction of said reactance, a capacitative reactance associated with said inductive reactance for effecting reduction of said inductive reactance to small value when said reactances are traversed by substantial current, means for impressing the oscillations of different amplitudes upon said winding and said inductive reactance, and means for impressing upon said reactances a periodic current of a frequency different from the frequency of said oscillations.

13. Radio receiving apparatus for distinguishing between oscillations of radio frequency representing a desired signal and oscillations of the same frequency but greater amplitude representing a disturbing effect, comprising a winding, signal-translating means associated therewith, an inductive reactance related to said winding for withholding energy therefrom upon reduction of said reactance, a capacitative reactance associated with said inductive reactance for effecting reduction of said inductive reactance to small value when said reactances are traversed by substantial current, means for impressing the oscillations of different amplitudes upon said winding and said inductive reactance, and means for impressing upon said reactances a periodic current of a frequency differing from the frequency of said oscillations by an amount effecting beats of inaudible frequency.

14. Apparatus for distinguishing between fluctuating currents of different amplitudes, comprising a winding and associated current-translating means; a reactance related to said winding for withholding energy therefrom upon reduction of said reactance, a reactance of different type associated with said reactance for effecting reduction of said first named reactance to small value when said reactances are traversed by substantial current, means for impressing the currents of different magnitudes upon said winding and upon said first named reactance, means for impressing upon said reactances a periodic current, and means for adjusting the magnitude of said periodic current.

15. Apparatus for distinguishing between fluctuating currents of different amplitudes, comprising a winding and associated current-translating means, a reactance related

to said winding for withholding energy therefrom upon reduction of said reactance, a reactance of different type associated with said reactance for effecting reduction of said 5 first named reactance to small value when said reactances are traversed by substantial current, means for impressing the currents of different magnitudes upon said winding and upon said first named reactance, means 10 for impressing upon said reactances a periodic current, and means for adjusting the magnitude of said periodic current to an amplitude corresponding substantially with the amplitude of the weaker of said 15 currents.

16. The method of distinguishing between fluctuating currents of different amplitudes, which comprises impressing the currents upon a current-translating circuit 20 and upon a control path upon the magnitude of whose reactance depends the magnitude of effect in said translating circuit, and impressing on the control path a fluctuating electro-motive-force for changing said 25 reactance for withholding from said translating circuit the effect of one of said currents to greater degree than the effect of another of said currents.

17. The method of distinguishing between 30 fluctuating currents of the same frequency but different amplitudes, which comprises impressing the currents upon a current-translating circuit and upon a control path upon the magnitude of whose reactance depends the magnitude of effect in said translating circuit, and impressing on the control path a fluctuating electro-motive-force for periodically changing the magnitude of said 35 reactance for periodically withholding to 10 different degrees from said translating circuit the effects of said currents of different amplitudes.

18. The method of distinguishing between fluctuating currents of different amplitudes, which comprises impressing the currents upon a current-translating circuit 45 and upon a control circuit including inductive and capacitative reactances, and impressing upon said control circuit a fluctuating current for periodically changing its reactance for periodically withholding to different degrees from said translating circuit the effects of said current of different amplitudes.

19. The method of distinguishing between fluctuating current of the same frequency but different amplitudes, which comprises impressing the currents upon a current-translating circuit and upon a control circuit including inductive and capacitative 50 reactances, and impressing upon said control circuit a fluctuating current of different frequency for periodically changing its reactance for periodically withholding to different degrees from said translating circuit 55

the effects of said currents of different amplitudes.

20. The method of distinguishing between radio frequency oscillations representing a desired signal and oscillations of the same 70 frequency but of greater amplitude representing a disturbing effect, which comprises subjecting to the influence of both sets of oscillations a signal-translating circuit and a control path including inductive and 75 capacitative reactances, and periodically varying the effective reactance of said control path for periodically withholding to different degrees from said signal-translating circuit the effects of both sets of said 80 oscillations.

21. The method of distinguishing between radio frequency oscillations representing a desired signal and oscillations of the same 85 frequency but of greater amplitude representing a disturbing effect, which comprises subjecting to the influence of both sets of oscillations a signal-translating circuit and a control path including inductive and capacitative reactances, and impressing upon said control path a periodic current of different frequency for periodically varying the reactance of said control path for periodically withholding to different degrees 90 from said signal-translating circuit the effects of both sets of said oscillations.

22. The method of distinguishing between sustained radio frequency oscillations representing a desired signal and decadent oscillations of the same frequency representing a disturbing effect, which comprises influencing by both sets of oscillations a signal-translating circuit and a control path including inductive and capacitative reactances, and impressing upon said control path 100 a current of different frequency for periodically varying the reactance of said control path for periodically withholding to different degrees from said signal-translating circuit the effects of both sets of said oscillations.

23. The method of distinguishing between radio frequency oscillations representing a desired signal and oscillations of the same frequency but of different amplitude, which comprises subjecting to the influence of both sets of oscillations a signal-translating circuit and a control path including inductive and capacitative reactances, and impressing upon said control path 115 a periodic current for varying the reactance of said control path for withholding to different degrees from said signal-translating circuit the effects of both sets of oscillations.

24. The method of distinguishing between radio frequency oscillations representing a desired signal and oscillations of the same frequency but of different amplitude, which comprises subjecting to the influence of both sets of oscillations a signal- 120

translating circuit and a control path including inductive and capacitative reactances, impressing upon said control path a periodic current for varying the reactance of said control path for withholding to different degrees from said signal-translating circuit the effects of both sets of oscillations, and varying the amplitude of said impressed current to a magnitude more closely 10 approaching the amplitude of the oscillations of one of said sets than the amplitude of the oscillations of another of said sets.

25. The method of distinguishing between sustained radio frequency oscillations 15 representing a desired signal and decadent oscillations of the same frequency representing a disturbing effect, which comprises subjecting to the influence of both sets of oscillations a signal-translating circuit and 20 a control path including inductive and capacitative reactances, impressing upon said control path a periodic current of different frequency for periodically varying the reactance of said control path for periodically 25 withholding to different degrees from said signal-translating circuit the effects of both sets of oscillations, and varying the amplitude of said impressed current to a magnitude more closely approaching the amplitude 30 of said sustained oscillations than the amplitude of said decadent oscillations.

26. Radio receiving apparatus for distinguishing between oscillations of radio frequency representing a desired signal and 25 oscillations representing a disturbing effect, comprising signal-translating means influenced by both sets of oscillations, a control path including capacitative and inductive reactances and so disposed that changes in 30 the reactance of said path cause said sets of oscillations to influence said signal-translating means to different degrees, and means for changing the reactance of said control path.

27. Radio receiving apparatus for distinguishing between oscillations of radio frequency representing a desired signal and oscillations representing a disturbing effect, comprising signal-translating means influenced by both sets of oscillations, a control 45 path including capacitative and inductive reactances and so disposed that changes in the reactance of said path cause said sets of oscillations to influence said signal-translating means to different degrees, and means 50 for periodically changing the reactance of said control path.

28. Radio receiving apparatus for distinguishing between oscillations of radio frequency representing a desired signal and 60 oscillations representing a disturbing effect, comprising signal-translating means influenced by both sets of oscillations, a control path including capacitative and inductive reactances and so disposed that changes in 65 the reactance of said path cause said sets of oscillations to influence said signal-translating means to different degrees, and means for impressing upon said control path a periodic current for changing its reactance. 70

29. Radio receiving apparatus for distinguishing between oscillations of radio frequency representing a desired signal and oscillations representing a disturbing effect, comprising signal-translating means influenced by both sets of oscillations, a control 75 path including capacitative and inductive reactances and so disposed that changes in the reactance of said path cause said sets of oscillations to influence said signal-translating means to different degrees, and means for impressing upon said control path a periodic current of different frequency for 80 periodically varying its reactness.

In testimony whereof I have hereunto affixed my signature this 13th day of November, 1922.

DAVID G. McCAA.
